UNITED STATES PATENT OFFICE.

EDWARD J. DARLING, OF PITTSBURG, PENNSYLVANIA.

COMBINED CHAIR, STEP-LADDER, AND TRESTLE.

SPECIFICATION forming part of Letters Patent No. 739,395, dated September 22, 1903.

Application filed January 20, 1903. Serial No. 139,761. (No model.)

To all whom it may concern:

Be it known that I, EDWARD J. DARLING, a citizen of the United States, residing at Pittsburg, in the county of Allegheny and State of Pennsylvania, have invented certain new and useful Improvements in a Combined Chair, Step-Ladder, and Trestle; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention comprises a combined chair, step-ladder, and trestle, the latter being particularly adapted to receive and support an ironing-board.

The object of the invention is to form an improved device of the kind stated adapted to a variety of uses and having certain advantages with respect to construction and facility of adjustment, as will appear more fully in the following description and claims.

In the accompanying drawings, Figure 1 is a side elevation of the device adjusted as a chair; Fig. 2, a similar view as a step-ladder. Fig. 3, a similar view, is a trestle supporting an ironing-board, and Fig. 4 is a front elevation.

Referring specifically to the drawings, 6 indicates the side bars, and 7 the steps, of the ladder. Two pairs of props are used in connection with this ladder, one pair being indicated at 8, which I will call the "ladder-props," and the other pair being indicated at 9, which I will call the "chair props or supporters." The latter are pivoted at their upper ends at 9^a to the side bars of the ladder, and the former—that is, the ladder-props 8—are pivoted at 8^a to the chair-props 9.

The ladder-props have suitable cross bars or braces 8^b, and the chair props or supporters have similar cross-bars 9^b. These cross-bars serve to brace and tie the props together and also to enter notches to hold the parts at the various adjustments, as hereinafter described. The cross-bars of the ladder-props support slats 9^c to form a comfortable back for the chair, and the upper of these slats are joined together by cross-pieces 9^d and hinged

to the top bar 8^b, forming a swinging section which serves as a bucket-shelf when swung out, as shown Fig. 2, by engaging under a round 6^b, which extends across between the side bars of the ladder under the top step thereof.

The chair-seat is composed of slats 10, which extend across between side frames 11, which are pivoted at 11^a to the side bars of the ladder at a proper height for the chair. The chair-seat is movable within or between the members of the props.

The side bars of the ladder have at the top and back edge thereof notches 6^a, which receive the topmost cross-bar 8^b, and at the bottom thereof notches 6^b, which receive the lowermost cross-bar 9^b. The seat-frames 11 have in the lower edge thereof notches 11^b, which receive one of the intermediate cross-bars 9^b.

To adjust the device as a chair, as shown in Fig. 1, the top cross-bar of the ladder-props is engaged in the lower of the notches 6^a and 75 the seat is projected through between the props and the parts locked in position by engagement of the intermediate bar 9^b in the inner notches 11^b.

To adjust the parts as a step-ladder, the top-most round of the ladder-props is engaged in the upper notches 6^a and the bottom of the props swung out until the intermediate bar 9^b engages the outer notches 11^b, forming a tie, which prevents further spreading of the 85 props. The ladder may then be mounted in safety.

To form a trestle, as indicated in Fig. 3, the ladder-props are disconnected at the top and swung around to engage the bottom cross-bar 9^b in one of the notches 6^b, and the ladder being turned to a horizontal position the props form cross-legs therefor. The series of notches 6^b permit the trestle to be adjusted to various heights. The seat hangs idle between the props when the parts are adjusted as a trestle, except when the trestle is let down to the last notch to form a washbench, when the lower ends of the seat-frame reach the floor and help to support the bench. On 100 the trestle so formed an ironing-board 12 may be laid, and cleats (indicated in dotted lines 12^a on the bottom of the ironing-board) enter between the steps and side bars of the ladder

and serve to prevent sliding of the board. The props are cut to proper length to rest on the floor when the parts are adjusted to form a chair. This forms a stable and strong support for the chair. The device may be folded into very small compass by detaching the cross-bars from the notches and folding the props, ladder, and seat to parallelism as near as may be.

10. What I claim as new, and desire to secure by Letters Patent, is—

1. The combination with a ladder, of two pair of props crossed and pivoted together, one pair being pivoted to the ladder and the other engageable with the ladder at either end thereof, and tie-bars joining the foot of the ladder and the props.

15. 2. The combination with a ladder having side bars notched at both ends, of the props 9

and notched seat-frames 11 pivoted to the said 20 bars, and the props 8 pivoted to the props 9, the latter having a cross-bar engageable in the notches of the seat-frames and the former having cross-bars engageable in the notches of the said side bars.

25. 3. The combination with a ladder, of props therefor, a seat pivoted to the ladder and supported by the props, and a vertically-swinging shelf hinged to the props and sustained in horizontal position by engagement with the 30 ladder, and forming when in vertical position a back for the seat, substantially as described.

In testimony whereof I affix my signature in presence of two witnesses.

EDWARD J. DARLING.
